UNITED STATES PATENT OFFICE.

CHARLES H. SPROESSIG, OF NEW YORK, N. Y.

COMPOUND USED FOR CLEANING.

No. 800,506.

Specification of Letters Patent.

Patented Sept. 26, 1905.

Application filed October 5, 1904. Serial No. 227,253.

To all whom it may concern:

Be it known that I, CHARLES H. SPROESSIG, a citizen of the United States, residing at 1400 Stebbins avenue, New York, State 5 of New York, have invented certain new and useful Improvements in Compounds Used for Cleaning, of which the following is a full, clear, and exact description.

The present invention relates to a compound which is preferably used for cleaning the hands and which removes therefrom all kinds of dirt, such as oil, tar, ink, paint, grease, &c.

In preparing said compound I proceed in the following manner: I take six quarts of wood-powder, two quarts of soap-powder, one quart of coal-oil, five grains oil of wintergreen, and one ounce of a solution of carbolic acid in about one hundred times its 15 volume of coal-oil and stir the mass thoroughly and intimately together. The resulting product is a compound in form of a fine powder which can be packed in cartridges and boxes either loose or in form of 20 cakes or any other suitable manner for shipment. To obtain the cakes, I use molds into which my compound powder is pressed by any suitable well-known device, or I may use a binder or suitable cement, so that the 25 30 particles of the powder are united.

In using my compound I wet one of my hands with water and sprinkle with the dry

hand the powder over it, whereafter by rubbing both hands against each other all grease paint, dirt, ink, oil, tar, &c., will be removed 35 from the skin and the hands will appear entirely white and clean after rinsing them in clean water.

As the compound contains no caustic constituents, the skin of the hands is not attacked, and after washing the hands they have not the slimy feeling given by caustics. Coal-oil and also coal-oil containing in solution a small quantity of carbolic acid do not adhere to the skin either, as they are 45 entirely taken up by the soap-powder and the wood-powder.

I do not limit myself to the exact proportions above given, for it is evident that the quantities of the ingredients may be varied 50 without departing from the nature of my invention.

Having thus fully described my invention, what I claim as new is—

A compound for washing which consists 55 of fine wood-powder, soap-powder, coal-oil, wintergreen and carbolic acid in approximately the proportions stated.

In testimony whereof I affix my signature.

CHARLES H. SPROESSIG.

In presence of—

FRITZ EPPLE,
JOHN HELMRICK.
